UNITED STATES PATENT OFFICE.

SYLVESTER HANKINS, OF ZEARING, IOWA.

HUSKING DEVICE.

1,156,478.

Specification of Letters Patent.

Patented Oct. 12, 1915.

Application filed December 31, 1914. Serial No. 879,819.

To all whom it may concern:

Be it known that I, SYLVESTER HANKINS, a citizen of the United States, residing at Zearing, in the county of Story and State of Iowa, have invented certain new and useful 5 Improvements in Husking Devices, of which the following is a specification.

This invention relates to improvements in husking devices, and one of the objects of 10 the same is to provide an improved hand device of this character, embodying a finger and palm engaging portions which though separated from each other are adjustably connected, whereby the device may be readily 15 and quickly adjusted to vary the length of the device.

A further object is to provide an improved 20 device of this character embodying a finger engaging hood or pocket having means whereby the size of the same may be varied.

To the attainment of these ends and the accomplishment of other new and useful objects as will appear, the invention consists 25 in the features of novelty in substantially the construction, combination and arrangement of the several parts hereinafter more fully described and claimed and shown in the accompanying drawing illustrating the invention and in which,

30 Figure 1 is a rear elevation of an improved device of this character, constructed in accordance with the principles of this invention. Fig. 2 is a front elevation of the parts shown in Fig. 1. Fig. 3 is a sectional view taken on line 3—3, Fig. 1. Fig. 4 is a 35 sectional view taken on line 4—4, Fig. 1.

Referring more particularly to the drawing, and in the present exemplification of 40 this invention, the numeral 10 designates a palm engaging plate having ears 11, 12 projecting therefrom and bent so as to curve over the edges of the hand. This plate is provided with a series of teeth 13 up struck therefrom, and the plate is preferably secured 45 to a flexible element 14, which rests against the palm, and a portion of this element is shaped to form a wrist encircling portion 15, having a strap 16 connected therewith, and a buckle 17 also connected 50 therewith coöperating with the strap. The ears 11, 12 also have a strap 18 and buckle 19 connected therewith for assisting in holding the device in position on the hand, and another strap 20 is connected with the up- 55 per portion of the element 14 and extends downwardly toward the bottom of the ele-

ment to pass through a slot or opening 21 in the strap 16, and the end of this strap 20 coöperates with a buckle 17. This strap 20 passes over the thumb so that when the device is in position, the strap may be drawn tightly and the thumb will be free.

A finger receiving pocket or hood 23 is secured to the front thereof, and the element 24 is provided with up struck teeth 25, 65 and the back of the pocket or hood is shaped to form a tongue or strap 26. A buckle 27 is connected by means of a short strap with the wrist encircling strap 16, and with this buckle the free end of the strap 26 is adjustably connected, so that the distance of the hood or pocket 23 with respect to the palm engaging portion may be varied to fit hands of different lengths. This tongue or strap portion 26 of the hood or pocket is 70 provided with a slot 28, and a strap 29 and a buckle 30 connected with the walls of the hood on opposite sides of the slot 28, so that the walls may be adjusted laterally with respect to each other to vary the width of the 80 pocket.

In use, the elements 14 and 10 are placed against the palm of the hand so that the ears 11, 12 will extend over the edge of the hand, and the strap and buckle 18, 19 are 85 connected. The thumb of the hand will pass through the opening 31 so as to be free, and the strap and buckle 16, 17 are connected. The strap 20 passing over the thumb is connected with the buckle 22 and drawn tightly 90 to make the elements 14, 15 fit the hand. The ends of the fingers are then inserted in the hood or pocket 23 and the device is then ready for use. In husking, the ear of corn 95 is grasped with the finger and palm guards and the thumb is free to take the husk off, and the ear of corn can be grasped with the right hand.

The plate 24 is preferably of a width slightly greater than the width of the hood or pocket so that the extremities 32 thereof may be formed into ears which bend over the edges of the hand.

What is claimed as new is:—

In a hand husking device, the combination of a palm engaging member and a finger engaging husking implement adjustably connected, said finger engaging implement embodying a closed hood for receiving and inclosing only the ends of the fingers, said 110 hood being shorter at the front than at the back, a toothed plate connected with the

hood, the ends of the plate extending over the sides of the hood, the sides of the back of the hood converging to form a centrally disposed narrow tongue integral therewith and extending along the back of the hand, said hood having a cut out portion extending into the tongue, and a strap and buckle connected with the hood and extending across the cut out portion beyond the edge 10 of the toothed plate on the hood to contract that portion of the hood, the space between

the palm engaging member and the toothed plate at the front of the device being entirely unobstructed and exposing the front of the fingers.

In witness whereof, I hereunto subscribe my name to this specification in the presence of two witnesses.

SYLVESTER HANKINS.
